H. C. F. MORANT

FILM DEVELOPING APPARATUS

Filed Oct. 22, 1920

Henry Charles Frank Monant
by - S. Angier, Atty.

UNITED STATES PATENT OFFICE.

HENRY CHARLES FRANK MORANT, OF HAWTHORN, VICTORIA, AUSTRALIA.

FILM-DEVELOPING APPARATUS.

Application filed October 22, 1920. Serial No. 418,666.

To all whom it may concern:

Be it known that I, HENRY CHARLES FRANK MORANT, a subject of the King of Great Britain, of "Monbulk," Riversdale 5 Road, Hawthorn, in the State of Victoria, Australia, have invented certain new and useful Improvements in Film-Developing Apparatus, of which the following is a specification.

10 In apparatus at present used in developing a length of photographic film during daylight no provision is made for observance of the development of the film or the development of individual negatives nor for controlling the time limit of immersion of each which is necessary in order to secure the best development of each negative where the exposure has been more or less faulty.

The present invention contemplates provision for the observance and immersion manipulation stated and this is attained by a box shaped receptacle or tank containing the developing solution provided with a glass celluloid or like cover of transparent material of a color that will prevent actinic light rays operating to affect the sensitive film.

In order to facilitate observance of the film during development the sides of the tank are fitted with one or more panels of 30 ruby colored glass or celluloid and a lamp is arranged to project light rays on to the film surface.

Manipulating means are provided within said box receptacle for detachably securing 35 the usual film spool and also external manually actuated means for rotating same to cause unwrapping of the film from one spool and its travel along the interior space to a receiving or transfer spool. Also within 40 the receptacle are means for depressing sections of the film into the developing solution during its travel from end to end of the box receptacle, and at the same time preventing the negative surfaces while immersed 45 contacting with other surfaces in the container.

One practical form of the invention is depicted in the accompanying drawings whereof—

50 Fig. 1 is a plan of the apparatus with the cover removed of a form of the invention for the independent development of negatives.

Fig. 2 a longitudinal vertical section through the apparatus. 55

Fig. 3 a vertical transverse section on line III—III, Fig. 2, and

Fig. 4 a fragmentary section on line IV—IV of Fig. 1.

As illustrated the apparatus comprises a 60 rectangular vessel 1 which may be subdivided by one or more partitions such as 2 to form separate receptacles 3—4 to contain respectively developing solution and water.

At opposite ends of the tank near the top 65 means are provided for conveniently attaching for rotation the film spool 5 and the transfer spool 6. As illustrated a short stud 7 is fixed on the wall and is adapted to engage the usual axial recess 8 in one end of the spool whilst the other end of the spool is attached to the end of a crank shaft 9 which enters the axial recess 10 of the spool and is provided with a transverse pin 11 the projecting ends of which engage end recesses 70 12 formed in the end of the spool. The shaft 9 extends through the wall of the tank and a bearing sleeve 13 thereon and is provided with means to rotate the shaft such as a crank handle 14. A spring 15 is wrapped 75 on the portion of the shaft between the tank wall and a washer 16 at the inner end of said shaft which maintains the connection of the spool with the shaft.

In order to release the spool the latter is 80 moved endwise against the pressure of the spring to free first the stud 7 and then the inner end of the crank shaft and by reverse action the spool is rotatably fitted in the tank. 85

The end of the wrapper attached to the film spool 5 is passed along the tank and its end is attached to the transfer spool 6 means being provided for insuring the film F as it is drawn from spool 5 to spool 6 90 being immersed in the liquid in the receptacles.

As illustrated the means consist of an im- 100 merser comprising a pair of arms 17 fixed to a shaft 18 rotatably mounted in the side walls of the tank one end of the shaft projecting through the wall and bent to form a crank handle 19.

Said arms bear upon the side edges of 105 the film and the arms of each imerser may be connected by a curved bridge piece 20.

Said arms and bridge piece may be formed of a suitably bent single length of wire the ends of which are fixed to the shaft 18 as illustrated whilst the downwardly projecting loops 30 act as guides for the film. It will be understood that by turning the crank arms a portion of the film, i. e. a single negative may be pressed down till fully immersed in the developing solution or the water.

A flanged metal cover 21 fits over the tank said cover having a ruby tinted glass panel 22 and provided with a hinged lid 23.

One side of the tank may be provided with ruby tinted glass panels 24 to admit light on the negative in each receptacle so that by looking down through the transparent panel 22 of the cover, the progress of development of each negative in succession may be observed.

In lieu of the transparent side panels an electric ruby tinted lamp 25 may be provided on the interior side of the tank wall as shown in Figures 1 and 2 said lamp being in circuit with a battery or other source of electric current.

In order to facilitate the washing of the negatives by the solution the bottom of the tank may be provided with rockers 26 on the underside.

In practice when developing negatives individually in the apparatus as illustrated, the developing solution and the water are supplied to the tank, the film spool is fitted to its crank shaft, and the end of the wrapper attached to the film is passed through the tank over the partition 2 and attached to the transfer spool 6, after which the cover is placed on the tank and the spool 6 is rotated to draw the sensitized film into the receptacle 3 containing the developing solution when the immerser arms are turned down to depress a negative into the solution. The tank is then rocked till by observation through the transparent panel of the cover it is ascertained that the negative is sufficiently developed when the spool 6 is rotated to bring the next negative into the solution and the previous one into the washing water contained in the next receptacle 4.

By this means each negative may be developed independent of the others of a film the completely developed film being wound

on the spool 6 which is then removed from the tank to enable the negatives to be immersed in a fixing bath.

I claim:

1. Improved film developing apparatus comprising a container for developing solution and having means for manipulating the film, said container having means to permit observation of the film and means to prevent passage of actinic light rays and a lamp arranged to project nonactinic light rays on the film.

2. Improved film developing apparatus comprising a container for developing solution and having means to permit observation of the film and means to prevent passage of actinic light rays, a film spool and a transfer spool each detachably mounted in the container.

3. Improved film developing apparatus comprising a container for developing solution and having means for manipulating the film, said container being arranged to permit observation of the film and prevent passage of actinic light rays, and means to immerse each negative in the developing solution and including operating means arranged exteriorly of the container.

4. Improved film developing apparatus comprising a container for developing solution and having means for manipulating the film, said container being arranged to permit observation of the film and prevent passage of actinic light rays, and film immersers each consisting of arms, a shaft to which said arms are fixed, said shaft being mounted in bearings in walls of the container and arranged with one end projecting through one wall, and a crank handle on said projecting end.

5. Improved film developing apparatus comprising a container for developing solution and having means for manipulating the film, said container having means to permit observation of the film and means to prevent passage of actinic light rays, and film immersers each consisting of a shaft mounted for pivotal movement in walls of the container and arms fixed to said shaft, said arms having projecting hooks at their ends.

Dated this 13th day of August, 1920.

HENRY CHARLES FRANK MORANT.
